CLOSED CIRCUIT GRINDING

Norman A. MacLeod, Britannia Beach, British Columbia, Canada, assignor of one-half to Alexander C. Munro, Britannia Beach, British Columbia, Canada

Application October 10, 1939, Serial No. 298,774

6 Claims. (Cl. 83—9)

This invention relates to closed circuit wet grinding systems and pertains particularly to a closed circuit grinding system adapted to deliver a coarse product to a continuously operating grinding mill such as a ball mill and to produce a classified ground product in a continuous process.

One of the particular objects of the invention is to provide a closed circuit wet grinding system which is characterized by the establishment of a predetermined rate of circulating load to give the maximum efficiency to the ball mill or other grinding apparatus.

A further object of the invention is to provide a closed circuit wet grinding system in which the moving parts are reduced to an essential minimum, particularly in the vicinity of the classifier portion of the system, whereby minimum interference with true settling in the classifier element is had, with a consequent increase in classification efficiency.

A further object of the invention is to provide a self-regulated wet grinding system employing a pump device to remove the discharge of settled material from a settling device to a grinding device, wherein a steady overflow of fines is obtained from the settling device independent of surges inherent in the operation of a pumping system under ordinary conditions.

A further object of the invention is to provide a wet grinding system in which fluctuations or surging in the system, as well as changes in dilution of the pulp passing through the system, have but a minor effect upon the operating conditions, whereby maximum efficiency of both grinding and classification are concomitantly secured.

The grinding system of the present invention involves the use of a settling tank adapted to receive the wet discharge of a wet grinding mill, preferably together with the original feed, and to separate the material delivered thereto into a relatively fine classified product and a relatively coarse reject product, discharge means receiving the reject product together with water from this classifying tank and including means for elevating the same to a level above the wet grinding mill, a second settling tank adapted to receive the elevated reject product and separate the same into two products, the one comprising principally the settled solid reject material which is introduced into the wet grinding mill and the other comprising the carrier water which is then discharged together with the above mentioned ball mill discharge and original feed into the first mentioned classifying tank.

Further objects and advantages of the invention will be brought out in the ensuing description of preferred embodiments of the invention, as illustrated in the accompanying drawing, or will be apparent therefrom. With reference to the drawing:

Fig. 1 is a partly schematic elevation of one form of the present closed circuit grinding system; and

Fig. 2 is a fragmentary detail illustrating a modification of the manner of introducing the feed to the system.

Referring to Fig. 1, a wet mill is indicated at 1, (it being appreciated that the term "wet mill" is employed in a general sense, to include the conventional ball mill, a rod mill, a tube mill, a chaser mill, or the like, operating with a carrier liquid such as water). The wet mill may comprise a ball mill, as shown, which is provided with conventional trunnions 2, an inlet 3 passing through one trunnion and a discharge 4 leading from the other trunnion. A classifying tank is indicated at 5, (the term "classifying tank" being used in a general sense to include various types of settling devices, such as a settling cone, a spitzkasten, or a settling tank member provided with submerged rakes or the like, as will be apparent to those skilled in the art). The settling tank 5 is provided with a surge box 6, a baffle 7 and an overflow weir 8, and the discharge pipe 4 from the ball mill 1 and the original feed pipe 9 are directed into the surge box 6. The settling tank 5 is provided at the bottom with a discharge line 11, preferably provided with a valve 12 and communicating to the inlet of a pump member 13 provided with a discharge line 14, valved as at 15, which discharges into a surge box 16 of a second classifying tank 17 located at a level above the ball mill 1. The classifying tank 17 is provided with an overflow weir 18 and a discharge line 19 communicating with the surge box 6 of the classifier tank 5. The settling from the classifying tank 17 are discharged from the bottom thereof as through a valved discharge line 21, communicating with the inlet line 3 above mentioned, to the ball mill 1.

In the use of the system, where a material such as an ore, together with a carrier liquid such as water, is introduced at 9 to the surge box 6 of the tank 5, the portion thereof which is of sufficient fineness that no grinding is required is overflowed from the tank 5 at the overflow 8 and the coarse or "sands" material is discharged through the line 11 to the pump 13 at a rate slightly greater than the desired rate of feed to

the ball mill. This withdrawn material is pumped up by pump 13 to the second classifying tank 17 from which the sands settle and flow through the pipes 21 and 3 to the ball mill at the desired rate of feed, that is, the discharge from the tank 17 is choked off at the valved line 21 so that a definite volume of water and material to be ground is supplied to the mill, a quantity less than that handled by the pump 13. The excess material handled by the pump 13 is discharged from the tank 17 as at 18 through the line 19 into the tank 5, to provide a continual return to the latter tank, wherefore any fluctuations which may occur in the pump operation, within the margins allowed for by the capacities of the various elements of the apparatus, will make no fluctuations in the quantity of the material supplied to the ball mill or in the rate of fluid overflow from the classifying tank 5, so that maximum efficiency of operation of the ball mill is secured together with maximum classifying efficiency of the tank 5. The only variant in the system is the original feed, which is normally maintained within close limits in any operation.

Through the use of a controlled discharge from the tank 17 to the ball mill 1, at the valved line 21, a positive rate of feed can be maintained so that the mill can be operated at a predetermined rate of circulating load such as to give maximum efficiency for the system, and the sands discharge from the classifying tank 17 to the ball mill 1 from a higher level is particularly advantageous from the standpoint of enabling a direct feed to the mill through the trunnion, avoiding the use of a scoop and scoop box; the surging of the system due to variations in the pump performance are substantially eliminated as far as the effect thereon upon the classifying operation of the tank 5 is concerned in view of the fact that any excesses resulting from such variations are closed-circuited through the overflow from the tank 17 to the tank 5, and these surgings are balanced in the closed circuit thus reducing to a minimum any disturbing effect on the classifier overflow at the tank 5.

The system presents the possibility of employing an additional control of the mill feed by the addition of water or other carrier liquid at the tank 17, as through a valved line 22, so that extra settling could be obtained if the tank were made sufficiently large by increasing the dilution of the pulp at this point, which results in increasing the percentage of solids in the feed to the ball mill over that in the material supplied to the pump from the tank 5, and at the same time the volume of the classifier overflow from the tank 5 would be increased.

The pump 13 is shown as being of the centrifugal type, which, when rubber lined, will give admirable service, but it will be appreciated that any other form of elevating means may be employed to carry the sands and water from the bottom of the tank 5 into the tank 17, without departing from the scope of this invention. It will be noted that the tank 17 is shown as being somewhat smaller than the tank 5, for the reason that the actual classification of material is accomplished at the tank 5 and the tank 17 may be relied upon merely to afford adequate settling of the sands for delivery thereof to the ball mill. Variations of the relative capacities of the several elements of the construction will occur to those skilled in the art, and it will be appreciated that

the herein disclosed relative proportions are exemplary only.

In Fig. 2 I have illustrated a modification of the system in which the original feed is introduced into the system at the position of the tank 17, instead of at the position of the tank 5 as shown in Fig. 1. Referring to this figure, a tank 17' is illustrated, provided with a sands discharge 21', a surge box 16', a valve inlet 15' communicating with a pump such as shown at 13 in Fig. 1, and an overflow 18'. A feed supply line 9' is shown, for introducing the feed to the surge box 16', according to this embodiment, and a liquid supply line 22' may also be provided if desired.

In the operation of a system provided with a separating tank of the type shown in Fig. 2 in which the feed is introduced at the upper separating tank, the first separation takes place in the tank 17', and the sands material is withdrawn through the discharge line 21' to the ball mill at the desired rate. The overflow from the tank 17' is then carried as through a conduit 19' to the surge box of the lower separating tank together with the discharge from the ball mill, and the overflow from this lower separating tank may be considered to be the finished product. The sands withdrawn from the lower separating tank and elevated to the surge box of the upper separating tank will thus comprise a relatively smaller quantity of material with a given ball mill throughput than is the case with the system shown in Fig. 1, but the sum of the materials admitted to the surge box 16' of the upper separating tank 17', i. e., the material supplied at 15' plus the material supplied at 9', will be in excess of the sands material withdrawn at 21' and supplied to the mill, wherefore the two substantially separate sands and overflow circuits are established in a manner comparable to that described in connection with Fig. 1, and the resultant elimination of surging effects is obtained.

I claim:

1. The method of grinding ores or the like which comprises: feeding the ore into a body of liquid in a gravity type of separating tank to separate the same into a fines product and a sands product in the presence of such liquid; discharging the fines product together with a portion of such liquid from said separating tank; separately discharging the sands product together with another portion of such liquid from the bottom of said separating tank under gravity flow; elevating said sands product and liquid; discharging said elevated sands product and liquid into a second separating tank to separate the same into a sands product and a liquid-containing fines overflow product; discharging said overflow product into said first separating tank together with said ore feed; discharging said last-mentioned sands product under controlled gravity flow from said second separating tank into a wet grinding device; and discharging the ground product from such wet grinding device into said first separating tank together with said ore feed and said overflow product from said second separating tank.
2. The method set forth in claim 1, in which the flow of sands product from the second separating tank to the wet grinding device is established at a rate of flow less than the rate of discharge of sands product from the first separating tank, wherefore a portion of the sands product and water from the first separating tank

is continuously returned to the first separating tank from the second separating tank.

3. The method set forth in claim 1, in which additional liquid is added to the circuit at the position of the second separating tank, whereby the pulp dilution is increased at this point in the circuit, and in which the flow of sands product from the second separating tank to the wet grinding device is established at a value less than the rate of discharge of sands product from the first separating tank, wherefore a portion of the sands product from the first separating tank is continuously returned to the first separating tank.

4. A closed circuit wet grinding system which comprises: a wet grinding element; a settling tank positioned to receive the discharge of said grinding element and provided with a feed inlet, a fines overflow at the upper portion thereof, and a sands discharge opening at the bottom thereof; conduit means communicating with said discharge opening and providing a gravity flow passage leading downward therefrom; elevating means in communication with said conduit means and positioned to receive the sands by gravity flow from said separating tank and elevate the same to a level above said wet grinding element; a second settling tank positioned to receive the elevated sands and provided with a bottom sands discharge and a top fines overflow; conduit means for conveying separated sands from said second settling tank to said wet grinding element; conduit means for conveying fines from said second settling tank to said first settling tank adjacent the position of said feed inlet,

and valve means in said first-mentioned conduit means for restricting the flow of sands to said wet grinding element.

5. A closed circuit wet grinding system which comprises: a wet grinding element; a settling tank disposed at a level below said wet grinding element and provided with an inlet, a bottom sands discharge, and a top overflow; a second settling tank disposed above said wet grinding element and provided with an inlet, a bottom sands discharge, and a top overflow; elevating means disposed below said first settling tank; conduit means connecting the sands discharge of the first settling tank with said elevating means for gravity flow thereto, conduit means connecting said elevating means with the inlet of said second settling tank, conduit means connecting the sands discharge of said second settling tank to the inlet side of said grinding element for gravity flow thereto and conduit means connecting the discharge side of said grinding element to the inlet of said first settling tank, to define a closed sands circuit; and conduit means connecting the overflow of said second settling tank to the inlet of said first settling tank, to complete an overflow circuit through said first settling tank, elevating means, and the second settling tank.

6. A closed circuit wet grinding system as set forth in claim 5, and comprising in addition, valve means in the portion of said first mentioned conduit means which connects the sands discharge of said second settling tank to said grinding element.
